UNITED STATES PATENT OFFICE.

PHILIP N. BRAUN, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

GARMENT PRESS.

Application filed October 18, 1923, Serial No. 669,230. Renewed September 23, 1927.

This invention relates to pressing machines, and more particularly to garment presses possessing improvements therein intended to produce efficient, smooth, quiet, and easily operated presses capable of producing great pressure.

A main object of the invention is to provide improvements in power pressing machines together with improvements in kick-off and press opening mechanism designed to absorb the opening stresses to allow the machine to open rapidly without strain and noise; and it is a further object to produce a pressing machine having facilities for closing the press lightly under initial jaw pressure, and subsequently increasing the compression between the closed press jaw members to produce final great pressure.

With the above principal objects in view, the accompanying drawings illustrate preferred embodiments of the invention serving to disclose the construction and mode of operation existing in my improved pressing machine. The machine may be varied in construction, operation and use without departing from the principles of my invention.

Figure 1 illustrates a side view of the pressing machine with all parts in open position; and Figure 2 illustrates a detailed sectional view of the improved cushioning device which functions during the opening movement of the press. Figure 3 shows a section upon the line 3—3 of Figure 1.

Referring now more particularly to the drawings for a further and detailed description of the invention, there is shown a pressing machine frame 5 upon which is pivoted at 4 a press lever 6. A press head or jaw 7 is carried on the forward end of the press lever while a depending link 8 is pivotally swung at 9 on the back end of the press lever. A head closing handle 10 is carried forwardly of the press lever or head by which the operator manually closes the head, and it is to be observed that a counter balance weight is employed to balance the head and other moving parts to cause the press lever to easily swing on its pivot 4. A bell crank or lifting lever 11 is pivoted at 12 on the frame; and a toggle bell crank, embodying an upper link 13 integral with a lower kick-off arm 14, is pivoted at 15 upon the

lower horizontal arm 16 of the lifting lever 11. It is observed therefore how the toggle bell crank 13—14 may be subjected to an up and down motion through the agency of the bell crank 11.

The forward end of the kick-off arm 14 is preferably provided with a detachable foot piece 17, and to this end the parts 14 and 17 may be provided with a shank and socket connection bolted together for the purpose of rendering it convenient to discard the pedal or mount it on the machine, depending upon the operator's wishes. The kick-off arm 14 is primarily designed to expedite the opening of the press, but it may be converted into a head closing pedal by using the foot piece 17 thereby enabling the operator to use his foot as well as his hands in closing the press.

A high pressure or power pedal 20 is pivoted at some suitable place on the frame and in this instance it is carried on the pivot pin 12. An adjustable link 21 connects the pedal 20 with a high pressure secondary toggle consisting of links 22 and 23, one of which is pivotally mounted on the frame, while the other end of this toggle is pivoted at 24 to the lifting lever bell crank 11; and it is observed how the toggle 22—23 is straightened by pressing the pedal 20 which oscillates the lift lever upon its bearing 12.

The pedal 20 is provided with an overhanging lug 39 and adjusting screw which reaches over into vertical alignment above the kick-off arm 14; and the lug is engaged by the rising kick-off arm during the opening of the press to bring to bear against all moving parts a cushioning effect carried out by my improved dashpot as will be described.

A pressing machine of this character develops great pressure with the expenditure of substantially little effort, and the operation of the pressing machine is convenient and easy to the operator because of the fact that the pedals 17 and 20, either or both, are located rather close to the floor thereby being operable by foot power without having to raise one's foot to any considerable height. And furthermore the machine is easy to operate because it closes in stages whereby one effort of the operator either by hand, by foot

- or both, closes the pressing machine to produce initial or light pressure; and thereafter the operator depresses the pedal 20 which forcibly oscillates the bell crank arm 16 upwardly through a short distance thereby lifting upwardly on the straightened toggle 8-13 which generates high compression between press jaws, i. e. the head 7 and buck or work support 18.
- 10 A pressing machine of such structure and generating extreme pressure, necessarily requires improved mechanism for smoothly opening the press, and to this end I provide improved kick-off means and a cushioning device. A dashpot 25 has a connecting rod 27 which attaches to the high pressure pedal 20, and the dashpot is preferably fixed upon the frame. After the pedal 20 is driven downwardly to produce extreme pressure and
- 15 following the release thereof, the force of the moving parts coming from under compression is very great by virtue of the release of the strain to which the entire machine is subjected, and the air confined in the cylinder 25 above piston 26 is quickly compressed to produce a smooth noiseless opening press movement. The pedal 20 having risen a part way and the air having become compressed and confined in the upper part
- 20 of the cylinder 25, it now becomes desirable to instantly and automatically open the dashpot to permit the compressed air to discharge therefrom in order that the remainder of the opening stroke be quickly accomplished; and
- 25 to this end I provide an automatic valve in the form of an exhaust port 29 located at the upper end of the dashpot cylinder 25, and the port is fitted with a hand regulating valve 19. A valve stem 30 provided with an
- 30 air exhaust passage 31 is carried on the piston and is adapted to reciprocate thru the cylinder head and over the port 29. Air intake ports 32 are located in the piston to admit air into the upper part of the cylinder
- 35 25 during the downward stroke of the pedal 20; and a loose flap valve 33 rests over the ports 32 to close them during the upward stroke of the piston and to open them during the downward piston stroke.
- 40 It is observed how the upper solid end of the valve stem 30 closes and seals the port 29 during a part of the piston travel, but when the piston has traversed a portion of the dashpot length, the passage 31 registers
- 45 with the exhaust port 29 and thereby releases the compressed air from the dashpot. It is significant that the air is not released but it is confined under pressure during the first few degrees of pedal movement thereby
- 50 thoroughly absorbing or dissipating the shock and strain incident to the expanding energy of the opening press, but after this object has been accomplished, the port 29 is automatically opened to permit the press
- 55 head 7 to continue its upward movement in a rapid manner unretarded by the dashpot except as by the escape of air thru the hand adjusted regulating valve 19 which is properly set by trial to secure the best results.
- 60 A kick-off or release pedal 35 is pivoted at 70 36 on the frame and is provided with a high pressure pedal kick-off or release means in the form of a screw 37 as well as a low pressure kick-off means such as an adjustable screw 38. The screws 37 and 38 are carried 75 in a separated manner upon the web or head of the release pedal 35 and are disposed under and in alignment with the pedal 20 and kick-off arm 14. When the head 7 is closed upon the buck 18, the kick-off arm 14 does not 80 quite reach the upper end of the screw 38 and therefore said pedal 35 possesses lost motion before it acts against the kick-off arm 14 to break the operating toggle 8-13 and lift the head 7; and it is this lost motion 85 which permits the other screw 37 to first thrust upwardly against the high pressure pedal 20 thereby first causing this pedal to rise, and immediately and subsequently the pedal 17 rises by virtue of the thrust of the 90 member 38 against the said member 14. Preferably the power pedal 20 goes down against the release screw 37; and the kick-off arm 14 goes down approximately to the screw 38 but stops short thereof which arrangement and adjustment of parts permits the high pressure pedal 20 to be first thrust upwardly to first remove the final high pressure from the machine prior to opening the press.
- 95 Springs 41 and 42 have their one ends fixed to the frame and the other ends attached to the pedals, and these springs facilitate the opening of the press and the lifting of the head high above the buck. During the first 100 opening stage of the press, the air lock in the dashpot prevents the pedal 20 from rising too rapidly, but immediately thereafter the spring 41 raises the pedal 20 to its normally upwardly limited position when the automatic valve in the dashpot opens to discharge the compressed air and relieve the air lock.
- 105 Trouble with pressing machines is sometimes experienced in the violent opening or rising of the head which causes the head to 110 kick back or rebound thus partly and prematurely closing the head when in fact it should remain up, and these difficulties are encountered by reason of the fact that the first few degrees of the head opening is permitted unopposed without any cushioning or retarding effort. Since the force of the opening of the press and lifting of the head is dissipated and the speed thereof is retarded in my invention by the closed dashpot, the 115 said head will not rebound and partway close and will not thereby reduce the efficiency of the machine as well as that of the operator.
- 120 As a further and final cushioning means, I provide a secondary cushioning function 125

in the form of a reduced or restricted air passage 40 which joins with the larger air passage 31, and this passage 40 practically closes the discharge port 29 by the time the 5 head 7 has reached its uppermost position, and the effect of the reduced air passage 40 is to again and for the second time confine or partly confine a small remaining quantity of air within the upper portion of 10 the dashpot to cause the head 7 to easily and quietly assume a position of rest when it opens, for as the head rises, the kick-off arm 14 rapidly overtakes the slower rising power 15 pedal 20 and quickly brings up against the overhanging lug or contact pad 39 thus in effect joining up the two heretofore independently moving parts 14 and 20, and this mode of operation now concentrates or directs all the opening strain of both independent 20 sets of mechanisms into one direct upward push against the dashpot piston; and the combined tension of the two springs 25 41 and 42 is exerted against the slowly discharging air cushion formed by virtue of the restricted dashpot valve passage 40.

I have therefore provided a dashpot possessing a compound air locking means having in effect a triple mode of operation in that the strain of the opening press parts 30 first react against a tight air cushion; and second the opening of the press quickly speeds up thru the unopposed pull of the coil springs; and thirdly the air lock is again and for the second time instituted to 35 easily bring the head to rest by slightly opposing opening motion of not only the high pressure pedal but the closing pedal and operating toggle 8-13 as well.

It is therefore seen that I have produced 40 a press wherein the handle 10 and/or pedal 14, with related parts toggle 8-13 and press lever 6, constitute operating means to open and close the press; and that high pressure or compression mechanism for producing 45 jaw compression resides, for instance, in the pedal 20 and its toggle 22-23 and bell crank 11 with related elements. The dashpot 25 is connected to the high compression mechanism to take and absorb the shock and 50 bound of the opening press.

Novel means, in the engaging or connecting lug 39, serves to engage or connect the operating means to the high compression mechanism so that one dashpot is effective 55 against the opening movement of the two independent sets of operating parts. It is significant that the connecting means 39 becomes operative only after the jaws have come from under high compression which 60 is an advantage because all the capacity of the dashpot is thus utilized to dissipate the very substantial force let loose in the machine when the press first opens. The pedal 14 and other parts of the operating means is 65 therefore free of the dashpot during the

period of compression relief but the dashpot is immediately connected with the operating means after the high pressure is relieved.

Also it is significant that while the two springs 42 and 41, pull separately, against 70 the operating means 14 and 8-13 to hasten the opening motion of the jaws, and also pull against the high compression mechanism 20 and 22-23 to return the same to non-compression position, nevertheless the 75 joint pulling effort of both springs is combined by the lug 39 touching pedal 14, to rapidly move the two independent sets of operating parts to normal position, this combining or joiner of the two springs taking place when pedal 14 overtakes the lug 39. Lug 39 therefore causes the force of 80 both springs, constituting a tensioning means 41-42, to exert itself against the single dashpot. Both springs combine into one, so to speak, to rapidly open the press and restore the high compression mechanism to inactive open position, but it is seen that each spring is free to act independently of the other during 85 the early period of the jaw opening movement.

Likewise the dashpot acts on one operating set only, namely the high pressure mechanism, during the early period of the opening movement, and thereafter acts on or against the operating means to retard the rebound of the heavy moving parts and press head 90 7 as they come to rest in open position.

What I claim is:

1. A pressing machine combination embodying relatively movable press members, operating means connected with one of the press members to close the press, a release means for opening the press, a dashpot connected with one of the press members to restrain the machine against sudden opening movement when released, means in the dashpot for locking the compressed air therein during the first portion of the stroke, means for releasing rapidly the air to hasten the opening movement during part of the remaining stroke, and means gradually diminishing the air release during the final part of the stroke and opening motion of the 100 press.

2. A pressing machine comprising a frame, a pressing member mounted thereon, a press lever pivoted in the frame, a press head carried by the lever, a depending link pivotally attached to the press lever, a bell crank having one arm pivotally connected to the depending link forming a toggle and having the other arm thereof extending toward the front of the machine, a lifting lever pivotally mounted in the frame with one end extending upwardly and the other end horizontally and pivotally supporting the bell crank, a handle on the press head to manually lower the head and straighten the toggle, a kick-off device to thrust upwardly 105 110 115 120 125 130

against the forwardly directed arm of the bell crank, a second named toggle connected with the lifting lever, and means to operate the second toggle.

5. A pressing machine comprising a frame, a pressing member mounted thereon, a press lever pivoted in the frame, a press head carried by the lever, a depending link pivotally attached to the press lever, a bell crank having one arm pivotally connected to the depending link forming a toggle and having the other arm thereof extending toward the front of the machine, a lifting lever pivotally mounted in the frame with 10 one end extending upwardly and the other end horizontally and pivotally supporting the bell crank, a handle on the press head to manually lower the head and straighten the toggle, a kick-off means to thrust upwardly 15 against the forwardly directed arm of the bell crank, a second named toggle connected with the lifting lever, means to operate the second toggle, and a foot piece attachable to the forwardly directed arm to convert it 20 into a pedal.

4. A pressing machine comprising a frame, a bell crank pivoted on the frame, a second bell crank pivotally carried by the first named bell crank and adapted to be 25 lifted thereby, a press head operated by the second bell crank, a buck carried by the frame, hand closing means on the head for closing the head and operating the second bell crank, a toggle connected with the first 30 named bell crank, a high pressure lever connected with the toggle, and a foot piece carried by the second named bell crank to facilitate the closing of the head.

5. A pressing machine comprising a frame, a bell crank pivoted on the frame, a second bell crank pivotally carried by the first named bell crank and adapted to be 40 lifted thereby, a press head operated by the second bell crank, a buck carried by the frame, hand closing means on the head for closing the head and operating the second bell crank, a toggle connected with the first 45 named bell crank, a high pressure lever connected with the toggle, and a kick-off means cooperating with the second bell crank to open the press.

6. A pressing machine comprising a fixed press member and a movable member, 55 a toggle connected with the movable member and adapted to raise and lower it upon the fixed press member, a kick-off arm carried by the toggle, a high pressure pedal having connection with the movable press member and adapted to impose high pressure 60 thereupon, a cushioning device connected with the high pressure pedal, and a connection established between the kick-off arm and the high pressure pedal whereby the cushioning device cooperates with both the 65 high pressure pedal and the kick-off arm.

7. A pressing machine embodying relatively movable pressing members and operating means to open and close the press, a high pressure lever adapted to impose high pressure on the press after the said press is 70 closed, a kick-off means to first relieve the press of high pressure and subsequently to open the press, a cushioning means possessing a positively closed air lock working against the press opening parts during the 75 first few degrees of opening movement, a device embodied in the cushioning means to relieve the air lock after the high pressure 80 has been removed from the press, a connecting means established between the high pressure lever and press closing means, and means for increasing the cushioning effect at the end of the opening stroke.

8. A press comprising, a frame, press jaws carried thereby, operating means to 85 open and close the jaws, high pressure mechanism to produce jaw compression, and a dashpot connected with the mechanism to first absorb the shock from the jaws as they are released from compression; and means 90 for thereafter applying the dashpot to the operating means after compression is released to retard the rebound of the jaws at the end of the jaw opening movement.

9. A press comprising, a frame, press jaws 95 carried thereby, operating means to open and close the jaws, high pressure mechanism to produce jaw compression, and a dashpot connected with the mechanism to first absorb the shock from the jaws as they are released from compression; and means carried 100 with the high pressure mechanism adapted to be engaged by the operating means so that the dashpot is effective against said operating means after compression is released.

10. A press comprising, a frame, press jaws carried thereby, operating means to open and close the jaws, high pressure mechanism to produce jaw compression, and a dashpot connected with the mechanism to 110 first absorb the shock from the jaws as they are released from compression; and a lug carried by the high pressure mechanism adapted to be engaged by the operating means to apply the dashpot against the latter after compression is released.

11. A press comprising, a frame, press jaws carried thereby; operating means to open and close the jaws including, a pedal, and means connecting the pedal to a jaw; 120 high pressure mechanism to produce jaw compression including, a pedal, and means connecting this last pedal to a jaw, a dashpot connected with the high pressure mechanism, and means to engage one pedal with 125 the other after compression is released to thereafter apply the dashpot against both pedals.

12. A press comprising, a frame, press jaws carried thereby, operating means car- 130

ried on the frame to open and close the jaws, and high pressure mechanism carried on the frame to produce jaw compression; a spring connected with the operating means to hasten the jaw opening movement, a spring connected with the high pressure mechanism to restore the same to non-compression position, and means whereby the operating means engages the high pressure mechanism so that both springs pull together during the final jaw opening movement.

13. A press comprising, a frame, press jaws carried thereby; operating means to open and close the jaws including, a pedal, and means connecting the pedal to a jaw;

high pressure mechanism to produce jaw compression including, a pedal, and means connecting this last pedal to a jaw; a spring connected to the first pedal to hasten motion of the operating means, a spring connected with the second named pedal to hasten motion of the high pressure mechanism, and means whereby the two pedals engage one another to cause the same to be simultaneously acted on by the springs.
